UNITED STATES PATENT OFFICE.

JOHN P. LYNN, OF CHICAGO, ILLINOIS, ASSIGNOR TO DUR-O-LITE PENCIL COMPANY,
OF CHICAGO, ILLINOIS, A CORPORATION OF ILLINOIS.

PENCIL.

Application filed May 20, 1926. Serial No. 110,518.

This invention relates to a pencil having a hollow body through which a lead may be fed into position for writing, and more particularly to certain means for mechanically advancing the lead, as desired. 5

In a pencil of this general character I have incorporated certain improvements which conduce to simplicity in construction and operation. For this purpose I associate 10 with the body a rotatable tip which induces travel of a propeller by which a lead is expelled through the tip end of the pencil. The construction of the tip, also its connection with the pencil body, presents certain 15 improved features which will be hereinafter set forth at length.

In the accompanying drawing is shown an exemplification of my invention in the manner following:

20 Figure 1 is a view in elevation of the pencil in its entirety;

Fig. 2 is a longitudinal section taken centrally therethrough;

25 Fig. 3 is a view, partly in elevation and partly in section, of the pencil tip per se;

Fig. 4, which is a similar view, shows the ferrule body expanded as when removed from the pencil;

30 Fig. 5 is a longitudinal section through the eraser holder detached from the pencil;

Figs. 6, 7, and 8 are enlarged transverse sections through the pencil taken, respectively, on lines 6-6, 7-7, and 8-8, of Fig. 2;

35 Fig. 9 is a fragmentary sectional view through a pencil tip of modified construction; and

Fig. 10 is a top plan view of the tip shown in Fig. 9.

40 The present pencil may comprise a body A having at one end thereof a rotatable tip B and at the opposite end a ferrule C wherein is retained an eraser by any suitable means. In the upper portion of the pencil 45 body is a chamber 11 forming a magazine for reserve leads and closed at its bottom as by a plate 12. Extending from the bottom of this chamber is an axial bore for the accommodation of a threaded propeller 13

50 having at its upper end a head 14 with a lateral projection which is slidably received within a slot 15 to one side of the bore. At its lower end the bore enters an enlarged chamber 16. At the point of juncture between the bore and chamber I provide a

transverse plate 17 having an opening through which the propeller body may freely move. This plate which is engaged by the head 14 when the propeller is advanced to its limit serves as a stop to prevent removal of the propeller from the pencil body. The walls of the chamber 16 are preferably lined with a bushing 18, as shown.

The body A of the pencil is preferably formed of a plastic material which can be 60 readily molded or pressed to the desired shape around the bushing 18, which serves as an anti-friction lining to the chamber 16.

The tip which I have designed for association with a pencil body so constructed 70 may be of metal or other material. As shown in Figs. 2, 3 and 4, the tip comprises an outer conical wall 20 straightened near its upper end into cylindrical form as at 21 so as to be fittable around the lower end of 75 the pencil body where an annular recess may be provided for accommodating the tip in flush relation therewith. Secured within the cylindrical portion of the tip is a head 22 from which upstands a tube 23 having 80 one or more longitudinal slots 24 therein. The normal tendency of the tube walls is to spring outwardly as indicated in Fig. 4, but when fitted within the bushing 18 they are straightened into substantial cylindrical 85 form, as in Fig. 3. In this manner, I provide a frictional connection between the tip and pencil body permitting the one part to be rotated relative to the other.

The walls of the tube 23 are turned at 90 the upper end to provide a depending cup 25 having screw threads therein which cooperate with those on the propeller 13. Joined to the cup is an inner tube 26 which extends substantially for the length of the tip to furnish a guide for the propeller and lead 27 therein. At its lower or constricted end the tip may be formed with one or more slots 28 providing spring sections between which the lead is gripped yieldingly. 95

100 A substantially similar construction of tip is set forth in Figs. 9 and 10. In this case the tip and tube are moulded as an integral product, the latter being provided with a cross slot 30 at its upper end. Surrounding the tube is a slotted sleeve 31 which tends normally to bow outwardly after the manner shown in Fig. 4. At its lower end the sleeve may be turned as at 32 to fit within a groove on the tube. To prevent rotation 110

of the sleeve upon the tip I provide at its upper end a cross wall 33 which is disposed within the slot 30. Depending from this cross wall is a threaded cup 34 adapted to 5 co-operate with the threads of the propeller 13 in the manner already explained.

With a pencil of the general kind described, I may associate an eraser 35 which, as shown, is provided with a cup-shaped retainer 36, the walls of which are slotted so 10 as to permit the retainer to spring outwardly as shown in Fig. 5. An eraser and retainer of this kind may be fitted within the ferrule C which acts to compress the cup 15 upon the eraser whereby it is held securely in place. If desired, the cup walls adjacent their upper edge may be outwardly beaded at 37 and then inturned at 38 to provide an edge which will bite into the eraser 20 when the parts are assembled in the position shown in Fig. 2. For purposes of ornamentation, any suitable cap may be applied over the eraser, if desired.

I claim:

- 25 1. A pencil having a body with an axial nonround bore which at its lower end is enlarged into a chamber, a screw-threaded propeller movable longitudinally through the bore and chamber, a tip removably associated with the pencil body having a cylindrical tube with outwardly sprung walls frictionally fitted within the chamber, an inner guide tube supported in the tip and cylindrical tube and providing a guide for a 30 lead and the propeller, screw means associated with one tube for engaging the screw threads on the propeller, and means on the propeller co-acting with the nonround bore in the pencil body for holding the propeller 35 against rotation, substantially as described.
- 40 2. A pencil having a body in which is an axial nonround bore communicating with an enlarged chamber at the lower body end, a screw-threaded propeller slidingly fitted within the nonround bore having means co-acting therewith for preventing its rotation therewithin, a tip fitted to the lower pencil end and provided with a cylindrical tube the walls of which are inturned at the upper 45 end to provide a screw-threaded cup for engaging with the threads of the propeller, and an inner tube joined to the cup extending lengthwise of the tip and providing a guide for the propeller, substantially as described.
- 50 3. A pencil having a body in which is an axial nonround bore which communicates with an enlarged chamber at the lower body end, a bushing fitted within the chamber to provide a cylindrical lining therefor, a tube longitudinally slotted to provide spring sections normally bowed outwardly adapted for fitting within the bushing, the tube walls being inturned at the upper end to form a cup 55 which is screw-threaded and adapted to en-

gage the threads of the propeller, a second tube within the first joined at its upper end to the cup thereof and extended therebelow to furnish a guide for the propeller, and tapering walls connecting the lower end of 70 the inner tube with the lower portion of the outer tube and fitting around the lower end of the body to provide a tip therefor, substantially as described.

4. In a pencil, the combination of a body 75 having an axial nonround bore the lower end of which is enlarged to form a cylindrical chamber, an apertured plate arranged transversely within the pencil body adjacent the lower end of the bore, a screw-threaded 80 propeller longitudinally movable through the bore and plate and retained by said plate, there being means for preventing rotation of the propeller within the bore, a tip fitted to the lower end of the pencil body and comprising an axial guide tube into which the propeller may advance, and means for supporting the upper end of the guide tube, comprising an outer tube joined to the tip and having cylindrical spring walls frictionally bearing against the inner face of the chamber and inturned at their upper 85 ends to connect with the inner tube, there being screw threads formed in the tube walls with which the threads of the propeller may engage, substantially as described.

5. In a pencil, the combination of a tip 90 having tubular double walls the inner of which furnishes a guide for a movable lead, a chambered body with which the outer tip walls are removably engaged, a threaded propeller movable nonrotatably through the chamber and extending into the guide, stop means independent of the tip for preventing removal of the propeller from the 95 body; and screw-threaded means associated with the tip for engaging the propeller to move the same longitudinally, substantially as described.

6. In a pencil having a chambered body, 100 a tubular sleeve forming a lining therein, the combination of a tip having an axial tube, said tube having outwardly bowed walls connected at their upper ends to exert a radial tension against the lining when the 105 tip is operatively associated with the pencil, a lead guide tube within said tip and axial tube, the tip being freely removable from and insertable into the pencil body, and a threaded propeller movable through the 110 chamber and tip, there being screw threads in the removable tip for engaging the propeller and means in the pencil body for preventing rotation of the propeller whereby upon rotation of the tip relative to the pencil 115 body the propeller is advanced longitudinally thereof, substantially as described.

7. In a pencil, the combination of a chambered body, a double walled tube formed internally with screw threads, the outer 120

wall having a weakened wall section intermediate its ends adapted for frictional fit within the body chamber and said inner wall forming a guide for a lead, a conical 5 wall of sheet metal forming the lower end of said tip and extended in spaced relation to the tube to surround the lower body end, and a propeller slidably non-rotatably within the body and in engagement with 10 the screw-threads of the tip, substantially as described.

8. In a pencil, the combination of a chambered body wherein is removably received a tube extending axially from a tip, the 15 tube walls being longitudinally slotted intermediate its ends to provide bowed spring sections which exert an outward pressure against the chamber walls whereby to assure a frictional connection therewith, a 20 lead guide extending centrally within said tube and tip and means operable by rotation of the tip relative to the pencil body for advancing a lead longitudinally thereof, substantially as described.

9. An automatic pencil comprising a 25 body of molded plastic formed with a chamber at one end thereof, a hard metallic tubular bushing rigidly mounted within said chamber and forming a lining therefor, a 30 removable tip having an outwardly bowed resilient tubular extension frictionally and rotatably mounted within said tubular bushing, a lead guide extending centrally within said tip and tubular extension. 35

10. An automatic pencil having a cylindrical body portion, a tip rotatably mounted therein for advancing a lead comprising a tapered lower portion and a relatively short tubular upper extension, said upper extension being of slightly less diameter than said lower portion and having a bowed portion intermediate its ends only for frictional engagement within said cylindrical body, whereby said tip may be readily withdrawn from or inserted into said chamber, and a 40 lead guide extending centrally within said tip and upper extension. 45

JOHN P. LYNN.
